UNITED STATES PATENT OFFICE.

EDWARD J. FLYNN, OF PARKERSBURG, WEST VIRGINIA, ASSIGNOR TO STANDARD OIL COMPANY, (INC. IN N. J.)

OUTAGE-GAGE.

1,378,536.

Specification of Letters Patent. Patented May 17, 1921.

Application filed December 15, 1919. Serial No. 344,785.

To all whom it may concern:

Be it known that I, EDWARD J. FLYNN, a citizen of the United States, residing at Parkersburg, in the county of Wood and State of West Virginia, have invented certain new and useful Improvements in Outage-Gages, of which the following is a specification.

This invention relates to certain new and useful improvements in an outage gage and it has for its primary object to provide an instrument for measuring the distance between the fluid contents of a tank car and the top of the shell thereof.

In the transportation of liquids, such as liquid fuels, the tank cars are ordinarily filled at loading point. Gasolene, being very volatile, is subject to evaporation and other loss in shipment which the shipper has to stand. This makes it very necessary to ascertain the exact quantity of liquid in the tank at the time it arrives at its destination. Heretofore, the contents were measured by inserting a graduated rod to the bottom of the tank and noting its submergence. This method, however, was unreliable for the reason that the agitation thus incurred causes the highly volatile liquid to boil up around the measuring rod thus obscuring the true level of the liquid.

The invention therefore aims to avoid this inaccurate method of determining the loss in content, and provides means which do not necessitate the insertion of the instrument in the liquid contents.

In the drawings.

Figure 1 is a front elevation of the improved outage gage;

Fig. 2 is a side elevation thereof;

Fig. 3 is a transverse section therethrough on line 3—3 of Fig. 1; and

Fig. 4 shows the application or manner of using the gage.

Referring more in detail to the drawing, the tubular body or frame 1 of the gage is preferably of U-section having overhanging opposing flanges 2 projecting inwardly from the upper edges thereof to confine and guide the slide rule or extension member 3 as well as to define a slot 4 through which a lift handle or hook 5, fixed on the upper end of the extensible member, projects.

Secured to the bottom of the body 1 is a right angular foot 6 having the base or horizontal arm flush with the bottom edge

of the body and extending laterally from the back face, and likewise fixed on the opposite face of the extensible slide is a second right angular foot 7 having the horizontal arm flush with its bottom edge and extending oppositely from the first foot, said foot piece 7 being disposed to enter slot 4 when the slide is completely telescoped.

When the measuring instrument is closed or telescoped, the slide is retained within the body against the closed upper end by means of a latch 8 pivoted to one flange 2 of the body and designed to swing across the slot below the lift hook and engage a keeper pin 9. By engaging the finger hold 10 or lip 10 on the latch the latter may readily be swung free of the hook 5 and the slide extended for measuring.

The length of the body, as well as that of the slide, is preferably twenty seven inches and each has the appropriate graduations 13 indicated thereon, those on the body reading down and those on the slide up whereby the reading may be made at either end.

In measuring the space above the liquid contents of the tank car indicated at 11, the foot 6 is abutted against the top of the shell, as at 12 and the slide 3 lowered until its foot 7 touches the liquid, the foot 7 making the instant of contact more pronounced. The instrument is then lifted and the measurement read either on the slide or on the body. This operation is simple and does not agitate the liquid to produce an untrue reading. The gage is compact and simply constructed as well as being economical in manufacture.

What is claimed is:

1. An outage gage comprising a tubular body slotted lengthwise throughout one side, a slide telescoping within the body and extendable beyond, a laterally extending foot on the outer end of both the body and the slide, said feet extending in relatively opposite directions, a lifting hook secured to the slide and projecting through the body slot, and a latch pivoted to the body on one side of the slot and adapted to swing across the slot in the path of the projecting hook to engage the same and thereby hold the slide within the body.

2. An outage gage comprising a tubular body slotted lengthwise throughout one side and closed at its inner end, a slide telescoping

ing within the body and extendable beyond the outer end thereof, a laterally extending foot on the outer end of both the body and the slide, said feet extending in 5 relatively opposite directions, means for operating the slide carried thereby and extending through the body slot, and means on the body coöperating with the first means and said closed end of the body to lock the 10 slide within the latter.

3. An outage gage comprising telescopic members, and a right angular foot piece secured to each with the horizontal arm of each foot piece extending laterally and in an opposite direction from the arm of the other foot piece, said horizontal arms being flush with the respective adjacent end faces of said members. 15

In testimony whereof I affix my signature.
EDWARD J. FLYNN.
